UNITED STATES PATENT OFFICE.

SAMUEL J. BLOCKER, OF DALLAS, TEXAS.

ANIMATED SIGN.

Application filed February 8, 1927. Serial No. 166,786.

This invention relates to animated signs.

An important object of the invention is to produce a device of this character in which the animated elements of the sign have a proper proportionate movement.

A further and more specific object of the invention is the provision of a sign including a base in perspective, which may be either modeled or painted having superimposed thereupon a number of movable objects forming a portion of the completed sign and means whereby these objects may be simultaneously moved in the proper proportion, as regards their position upon the perspective.

A still further object of the invention is to produce a device of this character which may be very readily and cheaply constructed, thus lending itself to use in the production of small advertisements and the like.

These and other objects I attain by the construction shown in the accompanying drawings, wherein for the purpose of illustration is shown a preferred embodiment of my invention and wherein:—

Figure 1 is a front elevation of an animated sign constructed in accordance with my invention, the relative movements of the parts being indicated by dotted lines;

Figure 2 is a rear elevation of the sign showing a form of operating means which can be conveniently employed.

In producing a sign in accordance with my invention, this sign is shown in the present illustration as having a base comprising a painted perspective 10 which is subdivided from the foreground F to the horizon H into a plurality of zones a, b, c, d, e, f, g, h, i, j and k. While no actual subdivision is made, these zones are suitably designated and preferably decrease in size from the zone a to the zone k in accordance with the laws of perspective. A plurality of movable objects 11, 12, 13, 14, 15 and 16 are superimposed upon the perspective, these objects being constructed in proper proportion to the position which they occupy in the perspective. It will be obvious that each of these objects will have its base located in a certain zone a to k of the perspective and in accordance with my invention, means are provided for imparting to this movable object a movement proportionate to the zone which it occupies, that is to say, if an article located in the zone a is given a certain movement, an article located in the zone h will be given a movement bearing the same pro-

portion to the movement of the article in the zone a as the zone h bears to the zone a.

As a ready means of imparting this movement to the movable articles, I provide a member 17, preferably concealed by the sign which is pivoted at 18. This member 17 is subdivided from the pivotal axis to its outer end into a plurality of zones corresponding to and proportioned similarly to the zones a to k of the base 10. These zones are in the present instance indicated as a' to k', the zone of the member which corresponds to the zone of the base being the prime of the ordinal indicating the zone of the base. To each of the movable objects 11 to 16, is secured an arm 19 which, in the present illustration, is disclosed as directed through the sheet 20 upon which the background is formed and extended in parallel relation to the back of the sheet. The arms 19 are all of the same length and extend in parallelism to the longitudinal axis of the sheet. To the member 17 are connected the ends of a plurality of links 21, the opposite ends of which are connected to the lower ends of the arms 19. The links 21 upon oscillation of the member 17 will move transversely of the sheet and by their connections with the arms will cause these arms to have an oscillation which is imparted to the movable object to which they are attached. The links 21 connected to the arms 19 of a given movable object are connected to the member 17 in the zone a' to k' corresponding to the zone a to k of the base in which the movable object is disposed. Thus, the head of the swan which has its base in the zone c of the base is connected through its arm to a link connected with the member 17 in the zone c', while the boat 14 which has its base arranged in the zone g has its arm connected to a link which is connected to the member 17 in the zone g'.

It will be obvious that if the links 21 are connected with the member 17 upon a common radius from the pivot 18 of the member, the movement imparted to the links 19 will be proportionate to the perspective position of the movable object with which they are connected and accordingly each movable object will have its proper relative movement in the perspective in which it is a part.

It will, of course, be obvious that under some circumstances, there will be movable objects to which it is desired that an ac-

centuated or exaggerated movement be given. Such objects I have illustrated in the movable objects 22 and 23 which are made in the semblance of fishing poles supported by fishermen who form a part of the perspective. To this end, the member 17 is preferably made in the form of a disk so that direct connection can be made between the member and the object to which the exaggerated movement is to be imparted, and so that a greater movement of the member is provided than that which is provided by the oscillatory arms connected to the members 11 to 16. In the present instance, the flexible elements 24 resembling fishing lines are connected to the poles, passed through openings 25 formed in the sheet 20 and connected directly to the disk. In the present showing, the connections to the disks are made in the zones corresponding to the zones in which the members 22 and 23 have their base or in the zones a' and f' respectively. If, however, a lesser movement of the members 22 and 23 is desired than that imparted by connecting the same in the zones in which the members have their base, this may be provided by shifting the connection inwardly a given number of zones. For example, the flexible element 24 of the member 22 could be connected to the zone c' and that of the member 23 in the zone b' . Thus, the proper relative movement of these elements with regard to the perspective is preserved and at the same time an exaggerated movement is given thereto.

Any suitable means may be provided for imparting an oscillatory movement to the disk. In the present instance, this disk is disclosed as equipped with a weight, causing the disk to act as a pendulum, so that an oscillatory movement imparted to the disk will be continued for some time. However, an operating means for oscillating the disk can be employed, if this is found desirable.

Since the construction hereinbefore set forth is capable of a certain range of change and modification without materially departing from the spirit of the invention, I do not limit myself to such specific structure except as hereinafter claimed.

I claim:

1. An animated sign comprising a perspective view including a stationary base including a plurality of zones proportionately decreasing in size from the foreground to the horizon of the view, a plurality of movable elements superimposed upon the view and

properly proportioned with relation thereto and means for simultaneously imparting movements to said movable elements in the proportion similar to the relative proportions of the zones of the view in which they have their base. 60

2. An animated sign comprising a perspective view including a stationary base including a plurality of zones proportionately decreasing in size from the foreground to the horizon of the view, a plurality of movable elements superimposed upon the view and properly proportioned with relation thereto, means for simultaneously imparting movements to said movable elements in the proportion similar to the relative proportions of the zones of the view in which they have their base, including a pivoted member subdivided from the pivot toward the free edge thereof into zones proportionate to the zones between the horizon and foreground of the view, operative connections between the movable elements and the pivoted member and means for oscillating the pivoted member. 65 70 75

3. An animated sign comprising a perspective view including a stationary base including a plurality of zones proportionately decreasing in size from the foreground to the horizon of the view, a plurality of movable elements superimposed upon the view and properly proportioned with relation thereto, means for simultaneously imparting movements to said movable elements in the proportion similar to the relative proportions of the zones of the view in which they have their base, including a pivoted member subdivided from the pivot toward the free edge thereof into zones proportionate to the zones between the horizon and foreground of the view including arms of equal length connected to each movable member and an operative connection between the free end of each of the arms and said disk in the zone of the disk corresponding to the zone in which the movable element of the arm has its base. 80 85 90 95 100

4. An animated sign comprising a stationary perspective view and a plurality of movable elements distributed about the view and means for simultaneously applying to said elements movements decreasing in intensity in proportion to the distance of the elements from the foreground of the view. 105 110

In testimony whereof I hereunto affix my signature.

SAMUEL J. BLOCKER.
